3 Claims. (Cl. 179—100.3)

Fixed density sound records are substantially produced according to two different methods. According to a first method, which is the older, the sound track is divided into two equal parts, 5 one transparent and the other opaque, during the periods of silence. During the periods of singing or conversation, elongations are recorded on either side of the axis of the track with an equal intensity, as shown in Figure 1 of the accompanying drawings.

When such a track is being translated into sound by passage across a luminous slit of constant length, the slit, during the periods of silence, allows a light band corresponding to half 15 its length to pass to the photo-electric cell, which produces a very unpleasant background noise.

According to the second method, shown in Figure 2, the track is substantially the same but it is enveloped by a black part which fills the transparent zone of Figure 1 as completely as possible. This is the arrangement called "noiseless" which considerably reduces the background noises during the silences or zones of weak modulation, in consequence of the suppression of a large part 25 of the light from the slit which fell uselessly on the photo-electric cell in the previous case.

There are other sound tracks derived from the preceding tracks and possessing the same properties, but for clearness of the description, only 30 the types according to Figures 1 and 2 will be considered, without limiting the invention only to this form of fixed density recording.

The process to be described makes it possible substantially to translate non-noiseless film by 35 means of a luminous slit, the length of which is constantly reduced to the mean value of the elongations of the sound track.

The present invention makes it possible to effect noiseless reproduction starting from a record of the type shown in Figure 1 without altering its appearance and without employing mechanical or electro-mechanical devices actuated in the course of operation, directly or indirectly, by the modulation recorded on the film, the invention employing a method of invariable illumination adjusted once and for all, which will be described hereinafter.

On the sound track of a sound film, the support of which is transparent, there is projected 50 a bright light so as to illuminate a rectangle ABCD, Fig. 3, having a length AB equal to the length of a cycle corresponding to a sound of lower pitch than the lowest sound which the amplifier and loudspeaker are able to render. If 55 for example this latter sound corresponds to 80

cycles, if the record has been made at a speed of 0.32 meter per second, and if the track is 2 mm. wide, it will be illuminated with a luminous rectangle 6 mm. long and 2.5 mm. wide. It is assumed that the sound track is bordered with black on both sides. The luminous flux passing through the sound track during the passage of a portion modulated at constant amplitude practically does not vary in each of the halves of the rectangle separated by the axis of the record. 10

The pencil of rays which has traversed the film is reutilized to form the image of the rectangle ABCD (Fig. 3) at A'B'C'D' in such a manner that the point A forms its image at A', B at B', C at C' and D at D', the line BC being substantially coincident with the line B'C'. Assuming the area of the luminous rectangle decomposed into elementary rectangles $a'b'c'd'$ and $a^2b^2c^2d^2$ parallel to the base AB, it will be seen that each of these rectangles forms its image $a'1a'2a'3a'4$ 20 and $a'2b'2c'2d'2$ on a corresponding zone of the rectangle A'B'C'D', it being possible to consider the center of BC as the center of symmetry. If the modulation is assumed to be substantially constant as to amplitude, it will be seen that all the elementary rectangles external of the modulation line will form their image in the unmodulated zones of the rectangle A'B'C'D', but the transparent elementary rectangles will form their image on the opaque portion of A'B'C'D', 30 while the opaque elementary rectangles will form their image on the transparent portions of A'B'C'D'. In other words, upon the second passage of the film by the rays of light, all the elementary rectangles outside the modulation in 35 its transparent portion and in its opaque portion will not allow light to pass, either because they do not receive any in the transparent portion or because they stop that which falls in the opaque portion. Light will therefore only be passed 40 through the elementary rectangles corresponding to the width of modulation. If, in particular, the modulation is zero, no light will pass through the rectangle A'B'C'D'.

A film thus illuminated, however, may give 45 rise to sound interference or beats due to superposing of the two translations, and this can be overcome by projecting the modulation of the rectangle ABCD while diffusing it in the longitudinal direction that is, the direction of film 50 movement, as hereinafter described.

Instead of effecting the translation by means of a mechanical slit placed at E'F', it is possible to employ a projection translation device, that is to say to project through an objective the 55

portion of the film adjacent E'F', so as to form a distinct image thereof on a mechanical slit of suitable width behind which is situated the photo-electric cell. The objective may further 5 more be replaced by a concave metal mirror producing the same effect.

A constructional form of apparatus according to the invention is shown in Figure 4 of the accompanying drawings. 1 is the filament of an 10 incandescent lamp producing by means of the condenser or objective 2 an image outlined along 3-4, its center being at 5 on the optical axis of the condenser. A concave mirror 6, the center of curvature of which is at 4 and the radius of 15 curvature of which is determined by the point of intersection 7 of the normal to the film at 4 with the optical axis of the condenser reproduces the image 3-5-4 at 3'-5'-4', the points 4 and 4' coinciding. At 8 is a grooved transparent 20 plate, and 9 is an objective lens assembly having two groups of lenses 10 and 11 which project an image of the portion of the film adjacent 5' on to the mechanical slit 12, behind which is a 25 photo-electric cell 13 of the barrier layer type, the distance of which from the optical system being adapted to the dimensions of the cell.

Fig. 4 shows by cross-hatching how the pencil of rays starting from the point 5 and reflected at the mirror 7 is diffused by the plate 8 over 30 the space 5a-5b. The film 14 moves over rollers 15 and 16 which may furthermore be replaced by any equivalent device adapted to the nature of the film employed.

The direction of movement of the film relatively to the system may be selected at will because, as may be shown graphically, the effect obtained during the passage of a rapid change of modulation remains acceptable, irrespective of the direction in which the sound records succeed 35 one another.

If the support of the film was made of an opaque reflecting material, the same means would obviously be applicable, except that the position of the concave mirror and that of the diffraction grating relatively to the film would be reversed.

Fig. 5 shows a non-noiseless record produced on a black coating deposited on the surface of a transparent film by gravelling by means of a gravelling tool having a rectilinear edge moving transversely. It is possible to apply the invention to a record of this kind by supposing the width of the track to be divided into two equal portions *a* and *b*, each of which is regarded as a normal 50 non-noiseless track on which the above-described light device is allowed to act. On the other hand, since each track *a* and *b* gives opposite effects,

they will be arranged in a push-pull connection having a double photo-electric cell which will enable the two effects to be added together instead of being cancelled.

The invention described makes it possible to produce directly on sensitised films noiseless copies starting from a non-noiseless record. For this purpose, it is merely necessary to cause a sensitive film to move in contact with the mechanical slit which, in the foregoing description, 10 has been assumed to be placed at E'F'.

I claim:

1. A method for the acoustic reproduction of fixed density sound tracks on films, which comprises illuminating intensely a certain length of 15 the sound track and redirecting the luminous flux falling on each of the half-widths of said track length onto each of the half-widths of an adjacent track length while inverting the redirected luminous flux so that the modulated 20 portion of the second track length receives exclusively the light which has passed through the modulated portion of the track length that has received direct illumination, and diffusing the redirected luminous flux exclusively longitudinally of the film before it reaches the second 25 length of the track.

2. A device for the acoustic reproduction of fixed density sound tracks on films, comprising a light source, an optical system for forming a rectangular image of the light source on a determined length of the sound track, a reflecting system for projecting said image onto an adjacent length of the sound track, means interposed in the path of the beam of light between the two illuminated track lengths for diffusing the said beam in the direction of film travel, and an optical system for projecting onto a photo-electric cell the image projected onto the second 30 length of the track.

3. A method of sound reproduction from a constant density sound track film, comprising directly illuminating a determined length of the sound track, redirecting the luminous flux falling on each half-width of said track length onto the half-widths of an adjacent length of sound track but inverting the redirected luminous flux in such a manner that the modulated portion of the second track length receives only the light that has traversed the directly illuminated first track length, and diffusing the redirected luminous flux in the direction of longitudinal movement of the sound track before said flux falls on said second track length and without modifying said luminous flux in the transverse direction.

ROGER BERNHEIM.
